J. H. WITTMANN.
CAMP FURNITURE.
APPLICATION FILED OCT. 22, 1917.

1,306,042.

Patented June 10, 1919.

THE NORRIS PETERS CO., PHOTO LINER, WASHINGTON, D. C.

UNITED STATES PATENT OFFICE.

JOSEPH H. WITTMANN, OF KANSAS CITY, MISSOURI.

CAMP FURNITURE.

1,306,042.

Specification of Letters Patent. Patented June 10, 1919.

Application filed October 22, 1917. Serial No. 197,826.

To all whom it may concern:

Be it known that I, JOSEPH H. WITTMANN, a citizen of the United States, residing at Kansas City, in the county of Jackson and 5 State of Missouri, have invented certain new and useful Improvements in Camp Furniture; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 My invention relates to camp furniture and more particularly to a table or the like, the principal object of the present invention being to adapt a camp bed structure of the type illustrated in my co-pending applications, Serial Nos. 86,974 and 143,273, for use 20 as a table in order that a camper or automobile tourist may have the benefit of both a bed and table, although required to carry but a single article, thereby saving space and 25 weight in transportation of his camp outfit.

While the present structure is substantially identical with that described in my previous applications, except for the improvement in the brace members hereinafter 30 described, I have, in order to give a better understanding of the invention, illustrated the entire structure in the accompanying drawings, wherein:

Figure I is a perspective view of a combination structure embodying my improvements and illustrating its use as a camp table, a part of the structure being broken away to show the supporting frame.

Fig. II is a side elevation of the same.

40 Fig. III is an end view of the same.

Fig. IV is a detail perspective view of a part of the under frame, particularly illustrating the attachment of the brace legs and the anchoring hook.

45 Fig. V is a detail view of the lower end of the tension bar, particularly illustrating the attachment of the clamp yoke.

Referring more in detail to the drawings:

50 1 designates the table top or apron, which is preferably composed of a single piece of heavy canvas or the like, provided at its opposite ends with pockets 2-3 for receiving cross bars 4-5. Attached to the cross bar 5 is a ground leg 6 which, when the table 55 is set up, extends at an incline beneath the

table to contact with a floor or the ground to support the table, and attached to the cross bar 4 is a tension bar 7 which is adapted for engagement with the upper edge of the ground leg 6 at an obtuse angle so that 60 when the table is so assembled and set up, any weight on the flexible apron 2, which would otherwise tend to effect scissor like closing of the ground leg and tension bar, merely serves to stretch the apron, because 65 of the thrust on the end cross bars induced by the tendency of the tension bar to move upwardly along the leg and thereby increase the distance between the ends of the leg and bar. To hold the parts together and restrain 70 the tension bar against sliding movement on the ground leg, I provide the bar with a clamp yoke 9, preferably comprising a U-shaped piece of strap metal of sufficient dimensions to slide freely over the ground leg, 75 and connected at its free ends by a rod 10, which is revolubly mounted in a sleeve 11 that is fixed to the tension bar by a strap 12, formed into a collar 13 and nailed, or otherwise permanently secured, to the tension bar, 80 the base of the yoke being adapted to seat against one of a plurality of seats 14 formed on a rack 14' that is fixed to the under side of the leg 6.

While the parts just described may form 85 a complete and substantial structure, when equipped with suitable means for anchoring one end of the frame to prevent its tipping either transversely or longitudinally, I prefer to connect the outer end of the tension 90 bar with the lower end of the ground leg by a rope or cable 15, having a buckle 16 whereby the tension of the rope or cable may be adjusted and secured. By so connecting the tension bar with the ground leg, the 95 table may be tensioned and assembled before it is erected, and when erected will retain its rigidity.

In order to brace and strengthen the 100 frame, I preferably provide the tension bar with brace arms 17, that may be connected with the bars through hinges 18 and attached to the ends of the cross bar 4 in any suitable manner, similar brace arms 19 being connected with the ground leg by hinges 105 20 and attached to the ends of the cross bar 5.

The parts heretofore described are similar to those described and illustrated in my prior co-pending applications, but in order 110 to adapt the structure for use as a table, I

- provide improved anchoring means, preferably comprising legs 22, here shown to consist of metal rods, having eye members 23 at their upper ends adapted for projection 5 over the threaded shanks 24, on the brace arms 19 and held rigidly in place by wing nuts 25 that take onto the threaded shanks 24 and clamp the eye members 23 to the brace arms. It is apparent that with this 10 mounting the threaded shanks 24 may serve not only to mount the brace rods, but also as attaching members for the hinges 26, whereby the brace arms are attached to the end cross bar 5.
- 15 To anchor the legs 22 against spreading, and thereby increase the rigidity of the table support, I mount anchor hooks 27 on the ground leg 6, preferably by connecting loops 28 at the inner ends of the hook shanks with 20 eye bolts 29 that are permanently attached to the ground legs, the outer ends of the shanks having the hooks 30 thereon adapted to take into apertures 31 on the legs 22 when the parts are in position.
- 25 With the parts so constructed the flexible apron may be rolled on the end cross bar 4-5, and the tension bar and leg members assembled in compact space, the brace arms folding against the bar and leg to avoid 30 projection therefrom, the hook rods 27 lying closely against the ground leg and the anchor legs 22 disconnected from the arm 19 and rolled in a bundle with the tension bar and ground leg.
- 35 When the table is to be set up the tension bar and ground legs are connected with the respective end bars 4-5, and the tension bar seated against the edge of a ground leg to stretch the apron, the clamp yoke 9 being 40 adjusted in the proper seat of the rack 14 and the rope or cable 15 adjusted to hold the inner end of the table down and retain the rigid assembly of the parts.
- The brace legs 22 are then attached to the 45 arms 19, the anchor hooks positioned in the link apertures 31 and the table set up on the single ground leg 6, pins 32 being projected through the feet 33 at the lower ends of the ground legs and driven into the

ground to brace the corners of one end of 50 the table.

When the table is so assembled and erected, it may be used for any suitable purpose, such as a dining table, during the day, and as a bed at night, thereby serving a 55 double purpose and obviating the necessity of carrying duplicate articles on a tour.

Having thus described my invention, what I claim as new therein, and desire to secure by Letters-Patent, is:

60

1. In combination with a flexible apron, a ground leg connected with one end of the apron, a tension bar connected with the opposite end of the apron and seating on the ground leg to form a supporting frame, and brace legs connected with one end of said frame and having fixed anchorage at their outer ends.

65

2. In combination with a flexible apron, a ground leg connected with one end of the 70 apron, a tension bar connected with the opposite end of the apron and seating on the ground leg to form a supporting frame, brace legs connected with one end of said frame and adapted for ground contact, and 75 anchor hooks connected with the frame and with the brace legs.

75

3. In combination with a frame comprising a ground leg and tension bar, a flexible apron carried by said frame, brace legs connected with opposite corners of one end of the frame and adapted for ground contact, and anchor hooks mounted on the frame and connected with the brace legs.

80

4. In combination with a flexible apron, 85 having cross bars at its opposite ends, a ground leg connected with one of the cross bars, brace arms connected with said cross bar and with the ground leg, brace legs removably attached to said brace arms and 90 adapted for ground contact, each of said brace legs having an aperture therein and anchor hooks connected with the ground legs and adapted for taking into the apertures in the brace legs.

95

In testimony whereof I affix my signature.

JOSEPH H. WITTMANN.
